UNITED STATES PATENT OFFICE.

PAUL TISHKEN, OF DETROIT, MICHIGAN.

GARAGE-DOOR HOLDER.

Application filed June 5, 1925. Serial No. 35,052.

This invention relates to door holders and relates particularly to devices for holding garage doors or other hinged closures in an open or partially open position.

It is an object of the invention to provide a door holder comprising a brace member pivotally mounted at one end upon a door and inclining downwardly from the door in use, the other end of said member being engageable with a surface above which the door swings, and to provide upon said door a supporting bracket for said brace member coacting with said member to hold the latter in an upwardly projecting stored position against the door, when desired.

Another object is to provide an improved construction of a two-part bracket for supporting a pivotal door brace or other member.

These and various other objects the invention attains by the construction hereinafter described and illustrated in the accompanying drawing, wherein:

Fig. 1 is a view in side elevation showing in full lines the position of use of the door holder, and in dash lines the stored position thereof.

Fig. 2 is a plan view of the same partially in section on line 2—2 of Fig. 1.

Fig. 3 is a front view of the supporting bracket.

In these views the reference character A designates a door and A' and A² designate two members forming a bracket mounted upon said door. The base of said bracket is formed by the member A' and the member A² has its mid portion embracing the mid portion of the base A' being thus held in unitary engagement with said base, the extremities of said member A² projecting as indicated at A³ transversely to the base A' and in spaced relation to receive a pivot pin B mounting a brace bar C. Preferably the mid portion of the base A' is offset slightly from the end portions thereof so that the bracket member A² in embracing said mid portion is restrained from any movement lengthwise of said base. The pivotal end of the bar C is longitudinally slotted as indicated at D to engage the pivot pin B and the other end of said bar is pointed as indicated at C' to dig into the ground or other surface above which the door A is adapted to swing.

The corners of the bar C at its pivotal end are rounded as indicated at C² so that said corners may readily clear the base mem-

ber A' as the bar is being swung from its position of use to its stored position or vice versa. In the stored position of said bar, the latter drops of its own weight so far as is permitted by the length of the slot D, thus assuming the dash line position shown in Fig. 1 and in this position contact of the lower end of the bar with the base member A' restrains the bar from swinging on its pivot pin. To establish the position of use of said bar, it is necessary only to lift the bar slightly so as to engage the pivot pin in the lower end of the slot D, it then being feasible to freely swing the bar upon said pivot.

In order that said bar may swing freely on the pin B, when engaged in the end of the slot D remote from the point C' of the bar, it is desirable to form said slot as Fig. 1 clearly shows adjacent to that edge of the bar which is undermost in the inclined position of use of the bar.

It is a feature of the described two-part bracket that the parts thereof are formed from duplicate stampings and that said parts are secured one to the other without fastenings other than the pivot pin B. These stampings may be produced from strap metal with no waste or from scrap material that would otherwise be wasted. The two part construction furthermore lends itself to the establishment of a spaced relation between the members A³ such as will prohibit side play of the bar C between said ends. The two part construction further permits the use of far simpler and less costly stamping dies than would be necessary for production of a similar one-piece bracket.

What I claim is:

1. A bracket comprising a pair of duplicate stampings, one having an intermediate portion offset slightly from the plane of its end portions and the other having its mid portion embracing the offset portion of the first mentioned member and having its end portions projecting transversely to the first mentioned member to form coacting supports.

2. A bracket comprising a stamped sheet metal member having its mid portion offset from the plane of its end portions, a second sheet metal stamping embracing the mid portion of the first mentioned member and having spaced portions projecting transversely to the first mentioned member and a pivot member connecting said spaced ends

and retaining the second mentioned stamping in the described engagement with the first mentioned stamping.

3. A bracket comprising a pair of sheet metal stampings, one having its mid portion forming a loop snugly embracing the other, and having its ends projecting in a spaced relation to each other and in a substantially perpendicular relation to the embraced stamping, the embraced stamping being fashioned to restrain said loop from shifting in the direction of the axis of the loop.

4. A bracket comprising two stamped sheet metal members, one transversely extending beneath the other and bent to form portions extending toward each other above the other, and further bent to form bearing portions projecting upwardly from the other in spaced relation, and further comprising a bearing member connecting said upstanding bearing portions.

In testimony whereof I sign this specification.

PAUL TISHKEN.
